PEN POINT ADAPTER FOR SCRIBERS

Manuel Chevillon, Arlington, Va.
(14506 Fairacres Road, Silver Spring, Md.)

Filed Nov. 14, 1956, Ser. No. 622,206

6 Claims. (Cl. 120—98)

The present invention relates to scribes such as are commonly used with templates for lettering purposes, etc., and has for its main object to provide those scribes which use other writing devices, with adaptors for using ordinary pen points in place of such other devices.

A further object of this invention is to make an adaptor pen point holder for use in place of other forms of writing devices, having a shank portion adapted for clamping in a scribe clamping element.

A further object is to provide scribes having clamping elements for gripping the shank portion of a standard printing tip, with a pen point holder having a similar shank portion adapted for mounting in said clamping elements, to enable the use of various types of pen points in said scribes in place of said standard printing tips.

A further object is to provide a stub shaft fitted with a pen point clamp thereon and adapted for mounting in a scribe in place of a standard printing tip.

A further object is to make a pen point holder adapted for mounting in a scribe clamp arm.

A further object is to form the above pen point holder from a single flat metal stamping.

Other and more specific objects will become apparent in the following detailed description of some forms of adaptors made in accordance with this invention, and illustrated in the accompanying drawing, wherein:

Fig. 1 is a plan view of one form of standard adjustable scribe with a simple pen point adapter mounted in its clamp arm,

Fig. 2, 4 and 6 are enlarged plan views of three different forms of simple pen point clamping means on an adaptor stub shaft of the type shown in Fig. 1,

Figs. 3, 5 and 7 are vertical sectional views of these devices, taken on the lines 3—3, 5—5, and 7—7 of Figs. 2, 4 and 6 respectively.

Fig. 8 is a plan view of another form of simple pen point adapter,

Fig. 9 is a vertical sectional view taken on the line 9—9 of Fig. 8, and

Fig. 10 is a blank sheet stamping of this adapter prior to its forming.

The standard form of scribe 11 shown in Fig. 1 is normally used in combination with guide templates for lettering, etc. This scribe has a fixed guide pin 12 at one end extending downwardly for cooperation with the base line guide of a guide template, and a guide pin 13 extending down from the end of an adjustable arm 14 which is pivoted at 15 and locked in adjusted position by clamp screw 16. This pin 13 cooperates with the guide template to guide the printing tip normally clamped in the end 17 of the clamp arm 18 by the clamp screw 19.

The device of the present invention, shown clamped in this clamp arm, comprises the stub shaft 20, having a reduced shank portion 21, substantially the same size as the shaft portion of the standard printing tip, mounted in the clamp in place of said printing tip, and a clamp ring 22 and set screw 23 holding a pen point 24 clamped

2

on said stub shaft 20 in proper writing or printing position.

The same adapter shaft 20 with the reduced shank portion 21 is used in the three modifications illustrated in Figs. 2 to 7. In the first of these modifications, as shown in Figs. 2 and 3, an eccentrically bored ring 25 is used so as to provide a greater thickness in which to tap the thread for the set screw 23.

In the second modification, the clamping means is a band 26 around the holder shaft 20, having a cam lever 27 pivoted between the end flanges 28 of the band 26 at 29.

Another simple way of clamping the pen point on this adapter shaft 20 is shown in the third modification, Figs. 6 and 7. This is a spring strip 30 formed and bored as shown, so that by pressing its ends together between the fingers it may be passed freely over the shaft 20, and will grip the shaft by expanding its ends when released. Thus the pen point 24 may be gripped in proper position between the shaft and the outwardly biased ends of the strip 30 pressing against the shaft at the bore.

Another form of adapter is shown in Figs. 8 to 10. This adapter may be formed from a single sheet stamping 31 of suitable spring material shaped and cut as indicated in Fig. 10. This sheet is sufficiently ductile to be bent and formed, as shown in Figs. 8 and 9; so that the lateral edges 32 and 33 of the sheet are brought together, the lower projections 34 and 35 form the hollow reduced shank portion 36 for mounting in the scribe clamp 17, the middle portion of the sheet being looped to form the hollow pen point holder 37, while the tongues 38 and 39 are offset inwardly of this loop to form a spring clip to receive and hold the pen point 24 against the inside of the hollow holder portion 37. The holder portion 37 is made to extend at an angle to the shank portion 36 whereby the pen point may be held at a suitable writing angle to the work surface.

By a suitable selection of sheet materials, this form of pen point adapter may be easily and cheaply made by die-cutting and forming.

It has been found that for some types of work the use of pen points of selected kinds is more suitable than any of the standard printing tips that are normally provided for use with the scribes. This is especially true where fine work is required, because printing tips are mainly designed for heavy lines. Furthermore, pen points are much easier to wipe clean, are ready for instant service, are cheaper and provide a greater variety of types that may be quickly changed to suit the requirements of finely distinctive work.

Although five different forms of the device are here illustrated, the invention is not limited to these specific forms, because it is obvious that many other modifications may be made without departing from the spirit and scope of this invention, as defined in the appended claims.

What is claimed is:

1. A pen point and printing tip holder combination comprising a pen point, means for holding said pen point in a downwardly extending writing position, said means including a reduced shank lying in a socket in said printing tip holder and extending downwardly from said holding means, an enlarged frame portion above said reduced mounting shank, the periphery of said enlarged frame portion extending over at least one side of said printing tip holder when said shank is mounted in the socket of said printing tip holder, said extending periphery being convexly curved to receive the upper end of said pen point on said side, and means for pressing said upper end of the pen point against said periphery.

2. A pen point and holder combination as defined in claim 1, said frame portion being an enlarged shank, said pressing means comprising a leaf spring clip normally

substantially bent in the form of a spread U, and having aligned bores through its sides when the outer ends of the sides are compressed during assembly into substantially parallel relation, the bores then being large enough to slip over the enlarged shank portion and the upper end of the pen point received thereby to facilitate assembly of said pen point and holding means, said sides when sprung apart over said upper end of the pen point after assembly being adapted to press it against said enlarged shank portion.

3. A pen point and holder combination as defined in claim 1, said pressing means comprising a clamp ring loosely fitting around said enlarged shank portion and having adjustable means for clamping against said upper end of the pen point.

4. A pen point and holder combination as defined in claim 3, said adjustable means being a set screw threaded through said ring.

5. A pen point and holder combination as defined in claim 3, said adjustable means being a bell crank pivoted 20 on the ring so that a wedge cam on one crank arm may

be clamped against the upper end of the pen point by operation of the other crank arm.

6. A pen point and holder combination as defined in claim 1, said holding means being formed from a single blank of sheet metal substantially of constant width except for downwardly extended ears at its ends, the mid portion of said sheet being rolled over to form the pen point holding means, the ends of the sheet being brought together and the ears rolled to form opposed halves of 10 said downwardly extending reduced shank.
